The ornamental design for a carrot nightlight, as shown and described.

DESCRIPTION

FIG. 1 is a front view of a carrot nightlight showing my new design;

FIG. 2 is a rear view thereof;

FIG. 3 is a side view thereof;

FIG. 4 is a top view thereof; and,

FIG. 5 is a bottom view thereof.

The light bulb is shown in broken lines for illustrative purposes only and forms no part of the claimed design.

FIG. 1

FIG. 2

FIG. 3

FIG. 4

FIG. 5
